MACHINE FOR OPERATING ON SHOES

John W. Pratt and William A. Barker, Leicester, England, assignors to United Shoe Machinery Corporation, Borough of Flemington, N. J., a corporation of New Jersey

Application March 17, 1939, Serial No. 262,488
In Great Britain April 28, 1938

25 Claims. (Cl. 12—123)

This invention relates to machines for operating on shoes, and is herein illustrated as applied to a machine for lasting the heel ends of shoes, the machine being one of the same type as disclosed in United States Letters Patent No. 1,949,539, granted on March 6, 1934 on an application of J. Gouldbourn, F. Ricks and W. T. B. Roberts. It is to be understood, however, that the invention is not limited to machines of that particular type and that in some of its aspects also it is not limited in utility to lasting machines.

A machine of the character disclosed in the above-mentioned Letters Patent comprises a heel band for embracing and clamping an upper about the heel end of a last, wipers for wiping the margin of the heel end of the upper inwardly over an insole or heel-seat piece on the last, and a jack which is mounted to swing in a direction lengthwise of the last from an initial work-receiving position to present the heel end of the last and upper within the heel band prior to the starting of the power operation of the machine, the jack including a post which is also movable upwardly to carry the shoe into contact with a hold-down which determines the position of the shoe heightwise relatively to the wipers. Such a machine is sometimes used for lasting the heel ends of shoes, such as some kinds of stitchdown shoes, the uppers of which are loose on their lasts, or at all events have not been previously subjected to the usual assembling and pulling-over operations, when the work is presented to the machine. Under those conditions it is customary for the operator to adjust the heel end of the upper heightwise relatively to the last and to maintain it at the correct height by holding it with his fingers in locations near the forward end of the heel seat until he starts the power operation of the machine. In order to relieve the operator of the necessity of thus holding the upper until the heel band assumes control of it, which it is sometimes difficult or inconvenient for him to do, the present invention, in one aspect, provides novel means for clamping the upper to maintain it in proper adjusted relation to the last. As herein illustrated, such clamping means comprises an auxiliary heel band arranged to be positioned between the main heel band and the upper during the lasting operation, and mechanism supported on the jack for applying the auxiliary band in clamping relation to the upper prior to the work-presenting movement of the jack. To permit this band to be maintained in proper relation to the upper, the construction herein shown is further such that the

band and the mechanism for applying it to the shoe are so supported as to partake of the upward movement of the jack post as well as the swinging movement of the jack, and also to partake of certain tipping movements and bodily lateral movements of the work which, in a machine of the illustrated type, the operator may effect to adjust the work in proper relation to the lasting instrumentalities. The machine herein shown is also provided with novel means for locking the auxiliary band in clamping relation to the upper and for thereafter releasing it as the jack returns to its starting position after the lasting operation.

In accordance with a further feature of the invention, the mechanism for applying the auxiliary band to the shoe comprises novel means whereby the band is first moved lengthwise of the shoe into clamping relation to the upper at the extreme end of the shoe and is then forced inwardly into clamping relation to the upper at the sides of the shoe. For this purpose the construction shown comprises levers which are connected to the ends of the band and, by depression of a treadle, are swung first lengthwise of the shoe and then laterally of the shoe, the swinging of the levers laterally of the shoe resulting from resistance of the shoe to the movement of the levers lengthwise thereof. More particularly, these band-applying levers are thus operated by the movement of a third lever connected to the treadle, this third lever being associated with a toggle device on which it fulcrums in its movement to swing the band-applying levers lengthwise of the shoe and which is yieldable thereafter to effect the movements of the band-applying levers laterally of the shoe. Provision is also afforded, by reason of the normal shape of the band and its resiliency, for applying it in clamping relation to the upper at the sides of the shoe first in locations at substantial distances from the edge of the last bottom and then progressively nearer the last bottom, as further insurance that the upper will be properly clamped without the presence of any objectionable wrinkles. In addition to maintaining the heel-end portion of the upper in proper adjusted relation to the last, the auxiliary band serves to conform the upper smoothly and tightly to the contour of the last before it is subjected to the heavier conforming pressure of the main band, and thus assists in the proper shaping of the upper. It will be recognized that with respect to the auxiliary band herein shown and the mechanism for applying it to the shoe, the invention in certain of its novel

aspects is not necessarily limited in utility to a machine in which there is also another band to operate on the shoe.

The above and other features of the invention, including various novel details of construction and combinations of parts, will now be more particularly described with reference to the accompanying drawings and thereafter pointed out in the claims.

10 In the drawings,

Fig. 1 is a view in left-hand side elevation of a portion of a machine in which the invention is embodied, showing the auxiliary heel band in clamping relation to the heel end of a shoe, parts 15 of the structure being broken away;

Fig. 2 is a view mainly in front elevation, on an enlarged scale, of a portion of the structure shown in Fig. 1 with the parts in the same positions as in Fig. 1 but with the position of the shoe 20 indicated diagrammatically by broken lines;

Fig. 3 is a view similar to the upper portion of Fig. 2, but showing the auxiliary heel band in its open position; and

Fig. 4 is a sectional view through a last pin on 25 the jack, and parts associated therewith, in a plane extending heightwise and laterally of the shoe.

Since the invention is herein illustrated as applied to a machine of the character disclosed in 30 the previously mentioned Letters Patent, only such parts as it is necessary to refer to for an understanding of the invention will be described in detail. The machine is provided with a shoe-supporting jack 1 mounted to swing, prior to the 35 starting of the power-operation of the machine, from an initial forwardly inclined work-receiving position to carry the shoe into position for its heel end to be embraced and clamped by a heel band 2, the lower portion of which is shown in Fig. 1. It will be understood that associated with 40 the heel band are wipers for wiping the margin of the heel end of the upper inwardly over an insole or heel-seat piece on the last, and a hold-down into engagement with which the heel end of 45 the shoe is carried by upward movement of a jack post 3, the wipers and hold-down being omitted from the present drawings. The jack is provided with a last pin 4 arranged to enter the spindle hole in the heel end of the last, this 50 last pin in the construction shown being fast in a block 5 (Fig. 4) which is mounted in a transverse guideway 6 formed in another block 7 supported on the upper end of the post 3. A screw 8 extending through a slot 9 in the block 5 and threaded at one end in the block 7 retains the 55 block 5 in place while permitting it to rock and also to move bodily with the last pin in directions widthwise of the shoe. The block 7 is mounted in arcuate guideways 10 in the post 3 for movement about an axis extending laterally 60 of the shoe and located substantially at the bottom of the heel end of the shoe. Accordingly the operator, before starting the power operation of the machine, may by control of the forepart of 65 the shoe and last tip them, together with the last pin, in one direction or another or move them bodily to the left or the right to position them in proper relation to the lasting instrumentalities. The top of the cone of the last when the latter 70 is mounted on the pin 4 rests on a plate 12 through which the pin extends, this plate being supported on the block 5 and being held thereon by a pair of leaf springs 13 which are fast on the block and extend into grooves formed in the 75 opposite sides of the plate. It will be understood,

therefore, that the plate 12 partakes of any of the above-mentioned positioning movements of the last pin 4 and the last mounted thereon.

For purposes of the present invention there is provided, in addition to the main heel band 2, 5 an auxiliary heel band 14 for clamping the heel end of the upper against the end and side faces of the last when the jack is in its work-receiving position and for holding the upper thus clamped as the jack is swung to carry the work into the 10 heel band 2. In order that the auxiliary heel band may be maintained in proper clamping relation to the upper as the work is raised by the post 3 and during any such tipping or bodily lateral movements of the last as above described, the 15 auxiliary band and the mechanism for applying it to the shoe are supported on the above-mentioned plate 12. To this end, the plate has secured to it a depending carrier 15 to which a casting 16 is secured by bolts 17. The casting 20 16 is provided at its opposite sides with guideways 18 for a frame 19 which, as viewed from above, is substantially U-shaped with its two limbs extending forwardly, this frame being bolted to the casting 16 with provision for upward or downward adjustment along the guideways 18. The forward end of each limb of the frame 19 has thereon a boss 20, and hollow pins 21 extending into these bosses provide a pivotal connection between the frame 19 and a second somewhat similarly shaped frame 22 the forwardly extending limbs of which lie at the inner sides of the limbs of the frame 19 but are inclined somewhat upwardly toward their rear ends. The frame 22 is provided with an upwardly and forwardly curved 25 lug 23 formed on the middle portion of the web which joins the rear ends of its limbs, this lug being of a hollow and substantially rectangular shape as viewed from the front (Fig. 2). A pin 24 secured in the opposite sides of the lug 23 provides a pivotal support for a depending lever 25, the pin being normally supported at a definite height, in order to prevent the frame 22 and the lever 25 from falling, by a connection hereinafter described between the lug 23 and heel-band 30 supporting levers 37.

The depending lever 25 has mounted therein, approximately midway between its upper and lower ends, a plunger 29 which is urged rearwardly by a spring 30 and bears at its rear end 35 against a face 31 on the frame 22, so that the spring tends to swing the lever 25 forwardly about the pin 24. The lever 25 is swung rearwardly about the pin 24 by mechanism hereinafter described, and by such movement of the lever the auxiliary heel band 14 is applied to the shoe. For this purpose there is rotatably mounted in an upstanding ear 33 on the lug 23 a rod 35 which extends widthwise of the machine, the rod being capable of moving lengthwise relatively to this ear a short distance determined by flanges 34 formed on the rod at the opposite sides of the ear. The opposite end portions of the rod 35 have right and left threads, respectively, formed thereon, and these portions of the rod extend through correspondingly threaded studs 36 on which are mounted the previously mentioned levers 37 which support the front ends of the auxiliary band 14. By means of a knob 38 the rod 35 may be turned to cause the upper ends of the levers 37 to approach or separate from each other as required by shoes of different widths. The studs 36 support the levers 37 substantially midway between the upper and lower ends of the levers, and in order to apply the auxiliary band 40 45 50 55 60 65 70 75 80 85 90 95 100 105 110 115 120 properly to the shoe provision is afforded for swinging movements of the levers first lengthwise of the shoe about axes at their lower ends to cause the band to clamp the upper against the 5 end face of the last and then laterally of the shoe about the studs 36 to force the forward ends of the band inwardly against the sides of the shoe. The lower ends of the levers are forked and are pivotally connected by pins 40 to the 10 enlarged heads of studs 39 which have hollow portions movable lengthwise and also rotatable within the previously mentioned hollow pins 21 on the frame 19. Springs 42 in the hollow portions of the studs 39 tend to force the studs inwardly toward each other. Between the inner 15 ends of the studs and the opposite sides of the lever 25 are links 41 having rounded ends seated in recesses formed in the studs and the lever. The links 41 are arranged to serve as a toggle between the studs 39 and the lever 25, and by the 20 action of the spring 30 on the lever 25 and of the springs 42 on the studs 39 the parts are normally so positioned that the links 41 extend forwardly at a substantial angle to each other. By reason 25 of the resistance of the springs 42 a rearward pull on the lower end of the lever 25 first causes the lever to swing about the inner ends of the links 41 as a fulcrum, so that through the pin 24 it swings the frame 22 forwardly about the hollow 30 pins 21. Since this frame is connected to the levers 37 by the rod 35, this movement of the lever 25 serves to swing the levers 37 forwardly about the axes of the studs 39 at their lower ends to apply the band 14 in clamping relation to the 35 end face of the upper. Thereafter, in response to resistance of the shoe to forward swinging movement of the levers 37, the lever 25 begins to swing about the pin 24 during a continued rearward pull on its lower end and therefore acts to 40 straighten more or less the toggle provided by the links 41 and thus to swing the levers 37 about the studs 36 to force the forward ends of the band inwardly against the sides of the shoe.

The upper ends of the levers 37 are forked and 45 carry pins 44 extending lengthwise of the shoe and on which are pivotally mounted blocks 48 secured to the forward ends of the band 14. This band is long enough to extend well forwardly of the heel-breast line of a large size shoe beyond 50 the portion of the upper clamped by the main band 2, and the upper edges of the band at its forward ends are arranged to press the upper against the sides of the last almost up to the edge of the insole or heel-seat piece on the bottom of 55 the last, the frame 19 being adjustable as described to position the band in the most appropriate relation to shoes having heel ends of different heights. The rear end portion of the band is arranged to extend so far downwardly as 60 to engage the upper close to the top edge of the counter, and therefore serves to hold this portion of the upper materials against movement away from the end face of the last during the lasting operation. This affords increased insurance that during the action of the wipers the 65 wings of the counter will not be displaced in a downward direction. The band consists of an inner layer 43 of thin flexible leather backed up by a layer 45 of thin resilient metal, the band as 70 a whole, therefore, being so formed as to accommodate itself readily to the heel ends of lasts of varying sizes and shapes. To increase the flexibility of the auxiliary band, it is so formed as to expose a portion of the upper lying between 75 the edge of the heel seat and a narrow portion

of the band extending continuously around the end of the upper near the top of the counter. In order to prevent the main band 2 from forming creases in the upper thus exposed by urging it forwardly along the sides of the last, the auxiliary band is provided with a pair of wings 46 extending rearwardly from its front end portions and arranged to be pressed against the upper by the main band as the latter closes around the shoe. The metal layer 45 of the auxiliary band, moreover, is so shaped as to cause the upper edges of the portions of the band at the sides of the shoe to flare somewhat outward relatively to the lower edges before the band engages the shoe, as illustrated in Fig. 3, and the connections between the band and the levers 37 are positioned near the upper edges of the band. By reason of this construction the lower edges of the band at the sides of the shoe engage the upper before the upper edges of the band and the area of contact of the band with the sides of the upper progressively spreads toward the edge of the last bottom as the levers 37 are swung inwardly. This serves to prevent the formation of wrinkles in the sides of the upper and causes the opposite side margins of the upper to extend well inward over the bottom of the last forwardly of the heel-breast line. The pins 44 which connect the band to the levers 37 may be readily removed to permit bands of different lengths to be mounted on the levers for use on shoes which differ widely in size. The levers 37 during their swinging movements are further guided and controlled by yokes 47 which are formed on the frame 22 and partially embrace the lower arms of the levers.

For operating the lever 25 to apply the band 14 to the shoe in the manner above described, there is connected to the lower end of the lever a wire 49 which extends partly around a small pulley 51 mounted on a downwardly extending portion of the casting 16 and is connected at its lower end to a treadle 52 pivoted on the frame of the machine. It will thus be seen that the lower end of the lever 25 is swung rearwardly by depression of the treadle. In order to hold the band in clamping relation to the upper when the operator releases the treadle 52, there is provided on the lever 25 an abutment 53 which is engaged by a latch 54 formed on a lever 55 pivotally mounted on the frame 19, this lever being controlled by a spring-pressed plunger 56 which tends to swing the latch upwardly but is yieldable to permit the abutment 53 to snap over the latch. There is further provided means for withdrawing the latch from the abutment to release the band-applying mechanism and permit the band to return to its initial position when the jack is swung forwardly to its initial position after the operation of the machine on the shoe. For this purpose the jack 1 has fast thereon an arm 57 which supports on its forward end portion a latch-releasing lever 59 pivotally mounted on a pin 60 on the arm. This lever, as shown, has an upwardly and rearwardly curved arm arranged to engage the lower end of the lever 55 and thus to swing the latch 54 downwardly in response to the forward swinging movement of the jack. Pivotally mounted on a pin 62 on a short forwardly extending arm of the lever 59 is a downwardly extending tubular casing 64 in which is mounted a plunger 66 engaged at its upper end by a spring 68 in the casing. Slidingly mounted in a forwardly extending lug 70 on the casing 64 is a rod 72 arranged to bear at its upper end against the arm 57 and controlled by a 75

spring 74 mounted between the lug 70 and a nut 16 on the rod. It will thus be seen that the spring 74 tends to swing the casing 64 in a rearward direction, such movement of the casing being limited by a stop screw 78 which is threaded in a lug 80 on the casing and is arranged to engage the arm 57. This screw is so adjusted that when the jack is in its forwardly inclined position the lower end of the plunger 66 lies in front of a plate 82 fast on the frame of the machine. It will be understood that as the jack is swung rearwardly the forward end of the arm 57 swings both rearwardly and upwardly, in which movement of the arm the spring 74 may yield by reason of engagement of the plate 82 with the lower end portion of the plunger 66 until the plunger has been lifted far enough to snap over the top of the plate. When the jack is swung forwardly after the completion of the lasting operation, the lower end of the plunger 66 is engaged by the top of the plate 82 and by the action of the plate on the plunger the lever 59 is swung in a counterclockwise direction (Fig. 1), the spring 68 being stronger than the spring 74. By this movement the lever 59 operates the lever 55 to cause the latch 54 to release the band-applying mechanism. As the jack nears the end of its forward swinging movement the plunger 66 snaps downwardly off the plate 82, permitting the parts to assume their normal positions illustrated in Fig. 1. When the band-applying mechanism is thus released by the latch 54 the frame 22 is returned to its initial position by a spring-pressed plunger 84 which is mounted in the frame 19 and engages a downwardly extending tail portion of the frame 22, and the lever 25 is swung forwardly about the pin 24 by the spring 30 and the springs 42.

In the use of the machine equipped with the above-described mechanism the operator first adjusts the frame 19 upwardly or downwardly, if necessary, to position the auxiliary band 14 at the proper height for the work to be operated upon, and also, if necessary, adjusts the forward ends of the band toward or from each other by turning the rod 35. If the machine is to operate on stitchdown shoes of a type in which the heel end of the upper is fastened in lasted position to a loose heel-seat piece as distinguished from a complete insole, the operator positions such a heel-seat piece on the bottom of the last and assembles an upper on the last with a counter in its heel-end portion. If he regards it as desirable, before mounting the last on the pin 4, he applies a pull to the toe end of the upper by means of hand pincers to tension the upper somewhat lengthwise of the last and drives a tack through the margin of the toe end of the upper to hold the upper in such tensioned condition. He then mounts the work on the last pin while the jack is in its forwardly inclined position and while the auxiliary heel band occupies the position illustrated by broken lines in Fig. 1. The operator next adjusts the extreme heel end of the upper into the desired position heightwise of the last and, by means of hand pincers or otherwise, applies an upward pull to the opposite sides of the upper just in front of the heel-breast line of the shoe to position those portions at the proper height and cause them to lie snugly against the sides of the last. While holding the upper in such adjusted relation to the last the operator depresses the treadle 52 to move the auxiliary heel band 14 first forwardly lengthwise of the last, and by further depression

of the treadle forces the forward end portions of the band inwardly into clamping relation to the upper at the sides of the last. By its forward movement the band serves to press the upper closely against the heel-end face of the last, especially near the top of the counter, and to work the upper forwardly along the sides of the heel portion of the last. As the forward end portions of the band are closed inwardly the band engages the sides of the upper first at substantial distances from the edge of the last bottom and then progressively nearer the last bottom to insure that the upper will be clamped smoothly against the last without objectionable wrinkles.

After the operator has thus applied the band to the shoe by depression of the treadle the band is held in clamping relation to the upper by the action of the latch 54 on the lever 25. The operator then swings the jack rearwardly to carry the heel end of the shoe into the main heel band 2 and raises the jack post 3 as usual to move the shoe upwardly to the position determined by the holdown. It will be evident that the auxiliary heel band and the mechanism for applying it to the shoe partake of the upward movement of the jack post, since they are supported by the plate 12 on the post, and they also partake of such tipping movement of the shoe in one direction or another, or such bodily lateral movement of the shoe, as the operator may effect in the manner hereinbefore described to position the shoe in proper relation to the lasting instrumentalities. It will be understood that the auxiliary heel band, in addition to holding the heel end of the upper in proper relation to the last during the movements of the jack, also serves as means for shaping the heel portion of the upper preliminarily about the last before the main heel band 2 becomes effective to perfect the shaping of the upper by its further clamping pressure about the heel end of the last. After the work has been properly positioned, the operator starts the power operation of the machine and the heel-end lasting operation is then performed in the manner characteristic of machines of the illustrated type. When the lasting operation has been completed the jack is permitted to swing forwardly to its initial position, and in this swinging movement of the jack the latch 54 is operated by the lever 59 to release the mechanism which operates the auxiliary heel band and permit this mechanism and the band to return to their starting positions.

While the invention has been described more particularly with reference to the lasting of stitchdown shoes, it is contemplated that it may be used also with beneficial results in the lasting of the heel ends of shoes of other kinds which have not been previously lasted along the sides of the shank portion, and that under some conditions, moreover, its use may be beneficial even though the shoes have already been lasted at the shank portion.

Having described the invention, what we claim as new and desire to secure by Letters Patent of the United States is:

1. In a machine for operating on shoes, the combination with a heel band for embracing and clamping an upper about the heel end of a last against the end and side faces of the last, and a work support movable from a work-receiving position to present the heel end of the last and upper within said band, of an auxiliary clamping device arranged to be positioned between said band and the upper for also clamping the upper

against the end and side faces of the last, and means for applying said auxiliary clamping device to the upper prior to the work-presenting movement of the work support.

5 2. In a machine for operating on shoes, the combination with a heel band for embracing and clamping an upper about the heel end of a last, and a work support movable from a work-receiving position to present the heel end of the last and upper within said band, of an auxiliary clamping device for clamping the heel end of the upper against the end and side faces of the last, and means for operating said auxiliary clamping device to clamp the upper first against 10 the end face of the last and then against the side faces of the last prior to the work-presenting movement of the work support.

15 3. In a machine for operating on shoes, the combination with a heel band for embracing and clamping an upper about the heel end of a last against the end and side faces of the last, and a work support movable from a work-receiving position to present the heel end of the last and upper within said band, of an auxiliary band arranged to be positioned between said first-named band and the upper for also embracing and clamping the upper about the heel end of the last against the end and side faces of the last, and means for moving said auxiliary band lengthwise of the last to clamp the upper against the end face of the last and for also moving its ends inwardly to clamp the upper against the side faces of the last prior to the work-presenting movement of the work support.

20 35 4. In a machine for operating on shoes, the combination with a heel band for embracing and clamping an upper about the heel end of a last, and a work support movable from a work-receiving position to present the heel end of the last and upper within said band, of an auxiliary band for also embracing and clamping the upper about the heel end of the last, and means connected to the ends of said auxiliary band for first moving it lengthwise of the last and then moving 40 its ends inwardly toward the sides of the last prior to the work-presenting movement of the work support.

45 5. In a machine for operating on shoes, the combination with a heel band for embracing and clamping an upper about the heel end of a last against the end and side faces of the last, and a work support movable from a work-receiving position to present the heel end of the last and upper within said band, of an auxiliary band arranged to be positioned between said first-named band and the upper for also embracing and clamping the upper about the heel end of the last against the end and side faces of the last, and mechanism carried by the work support and 50 connected to the ends of said auxiliary band for applying it to the upper.

55 6. In a machine for operating on shoes, the combination with a heel band for embracing and clamping an upper about the heel end of a last, and a work support movable from a work-receiving position to present the heel end of the last and upper within said band, of an auxiliary band arranged to be positioned between said first-named band and the upper for also embracing and 60 clamping the upper about the heel end of the last, said auxiliary band having end portions arranged to extend toward the toe end of the last beyond the portions of the upper embraced by said first-named band, members carried by 65 the work support and connected to said end por-

tions of the auxiliary band, and means for operating said members to move the auxiliary band lengthwise of the last and to force its end portions inwardly toward the sides of the last.

7. In a machine for operating on shoes, the combination with a heel band for embracing and clamping an upper about the heel end of a last, and a work support movable from a work-receiving position to present the heel end of the last and upper within said band, of an auxiliary band arranged to be positioned between said first-named band and the upper for also embracing and clamping the upper about the heel end of the last, and mechanism carried by the work support and connected to the ends of said auxiliary band for first moving it lengthwise of the last to clamp the upper against the end face of the last and for thereafter moving its ends inwardly to clamp the upper against the side faces of the last.

20 8. In a machine for operating on shoes, the combination with a heel band for embracing and clamping an upper about the heel end of a last, of an auxiliary band arranged to be positioned between said first-named band and the upper for also embracing and clamping the upper about the heel end of the last, said auxiliary band having end portions arranged to extend toward the toe end of the last beyond the portions of the upper embraced by said first-named band, 30 and means connected to said end portions for applying the auxiliary band to the upper.

25 9. In a machine for operating on shoes, the combination with a heel band for embracing and clamping an upper about the heel end of a last, of an auxiliary band arranged to be positioned between said first-named band and the upper for also embracing and clamping the heel end of the upper, said auxiliary band having an upper-clamping portion formed to extend continuously around the heel end of the last in a location spaced a substantial distance heightwise of the last from the edge of the last bottom and also having wings arranged to project heelwardly in spaced relation to said continuous portion for clamping the upper in locations nearer the edge of the last bottom, and means for applying said auxiliary band to the upper before the upper is clamped by said first-named band.

35 10. In a machine for operating on shoes, the combination with a heel band for embracing and clamping an upper about the heel end of a last, and a work support movable to carry the last and upper lengthwise to a position within said band, of an auxiliary band arranged to be positioned between said first-named band and the upper for also embracing and clamping the upper about the heel end of the last, said auxiliary band having an upper-clamping portion formed to extend continuously around the heel 40 end of the last in a location spaced a substantial distance heightwise of the last from the edge of the last bottom and also having wings arranged to project heelwardly in spaced relation to said continuous portion for clamping the upper in locations nearer the edge of the last bottom, and means for applying said auxiliary band to the upper before the last and upper are carried into position to be clamped by said first-named band.

45 11. In a machine for operating on shoes, a band for embracing and clamping an upper about the heel end of a last, said band having an upper-clamping portion formed to extend continuously around the heel end of the last in a location 50

- spaced a substantial distance heightwise of the last from the edge of the last bottom and also having wings arranged to project from its end portions heelwardly for clamping the upper in 5 locations between said continuous portion and the edge of the last bottom.
12. In a machine for operating on shoes, a band for embracing and clamping an upper about the heel end of a last, said band having an 10 upper-clamping portion formed to extend continuously around the heel end of the last in a location spaced a substantial distance heightwise of the last from the edge of the last bottom and also having resilient end portions normally 15 flaring in such relation to each other as to engage the upper first at a distance from the edge of the last bottom and then nearer said edge as said end portions are forced inwardly toward the sides of the last, said end portions 20 of the band being provided with wings arranged to project heelwardly therefrom for clamping the upper in locations between said continuous portion and the edge of the last bottom.
13. In a machine for operating on shoes, the 25 combination with means for operating on the heel end of an upper on a last, of a jack movable to carry the last and upper lengthwise toward said operating means and including an upwardly extending post movable upward relatively to the 30 other portions of the jack to lift the work, a device for clamping the upper against the heel end of the last, and mechanism movable to force said device against the upper prior to the movement of the jack, said mechanism being supported on said post so as to move upwardly with the post.
14. In a machine for operating on shoes, the 35 combination with means for operating on the heel end of an upper on a last, of a jack movable to carry the last and upper lengthwise toward said operating means and including an upwardly extending post movable upward relatively to the other portions of the jack to lift the work, a band for embracing and clamping the upper 40 about the heel end of the last, and mechanism connected to the ends of said band for supporting it and for applying it to the upper, said mechanism being supported on said post so as to move upwardly with the post.
15. In a machine for operating on shoes, the 45 combination with means for operating on the heel end of an upper on a last, of a jack movable to carry the last and upper toward said operating means and including an upwardly extending post having at its upper end a heel-end 50 support movable with the last relatively to the post to permit adjustment of the last, a device for clamping the upper against the heel end of the last, and mechanism movable to force said device against the upper, said mechanism being mounted on said heel-end support so as to partake of the adjusting movements of the last.
16. In a machine for operating on shoes, the 55 combination with means for operating on the heel end of an upper on a last, of a jack movable to carry the last and upper toward said operating means and including an upwardly extending post having at its upper end a heel-end support mounted to tip with the last relatively to the 60 post to permit adjustment of the last, a band for embracing and clamping the upper about the heel end of the last, and mechanism comprising members connected to the ends of said band and movable lengthwise and widthwise of the 65 last to force the band against the upper, said 70

mechanism being mounted on said heel-end support so as to partake of the tipping movements of the last.

17. In a machine for operating on shoes, the combination with means for operating on the heel end of an upper on a last, of a work support movable to carry the work toward said operating means, a band for embracing and clamping the upper about the heel end of the last, mechanism carried by said work support for applying said band in clamping relation to the upper, a latch for retaining said mechanism in band-applying position, a lever carried by the work support, and relatively stationary means arranged to operate said lever to withdraw the latch from operative position in response to return movement of the work support.

18. In a machine for operating on shoes, the combination with a band for embracing and clamping an upper about an end of a last, of a mechanism for moving said band lengthwise of the last to clamp the upper against the end face of the last, and additional mechanism arranged to act in response to resistance of the last to the movement of the band lengthwise thereof to force the ends of the band inwardly toward the sides of the last.

19. In a machine for operating on shoes, the combination with a band for embracing and clamping an upper about an end of a last, of members connected to the ends of said band, mechanism for moving said members lengthwise of the last to cause the band to clamp the upper against the end face of the last, and additional mechanism operative in response to resistance of the last to the movement of said members lengthwise thereof to move the members widthwise of the last and thereby cause the band to clamp the upper against the side faces of the last.

20. In a machine for operating on shoes, the combination with a band for embracing and clamping an upper about an end of a last, of members connected to the ends of said band, mechanism for moving said members lengthwise of the last to cause the band to clamp the upper against the end face of the last, spring-controlled devices yieldingly movable in response to resistance of the last to the movement of said members lengthwise thereof, and means for moving said members widthwise of the last by the movements of said devices to cause the band to clamp the upper against the side faces of the last.

21. In a machine for operating on shoes, the combination with a band for embracing and clamping an upper about an end of a last, of levers arranged to extend heightwise of the last and connected to the ends of said band, mechanism for swinging said levers lengthwise of the last to cause the band to clamp the upper against the end face of the last, and additional mechanism arranged to act in response to resistance of the last to the swinging of the levers lengthwise thereof to swing them widthwise of the last and thereby cause the band to clamp the upper against the side faces of the last.

22. In a machine for operating on shoes, the combination with a band for embracing and clamping an upper about an end of a last, of members connected to the ends of said band, an operating lever, means for moving said members lengthwise of the last by movement of said lever about one fulcrum to cause the band to clamp the upper against the end face of the last, and means for moving said members widthwise of the last by movement of said lever about a dif- 75

ferent fulcrum to cause the band to clamp the upper against the side faces of the last.

23. In a machine for operating on shoes, the combination with a band for embracing and clamping an upper about an end of a last, of members connected to the ends of said band, an operating lever, mechanism for moving said members lengthwise of the last by swinging movement of said lever to cause the band to clamp the upper against the end face of the last, and fulcrum means for said lever yieldingly movable in response to resistance of the last to the movement of said members lengthwise thereof, said members being movable widthwise of the last in response to the yielding movement of said fulcrum means to cause the band to clamp the upper against the side faces of the last.

24. In a machine for operating on shoes, the combination with a band for embracing and clamping an upper about an end of a last, of band-applying levers arranged to extend heightwise of the last and connected to the ends of said band, an operating lever movable to swing said band-applying levers lengthwise of the last to cause the band to clamp the upper against the end face of the last, and fulcrum means for

said operating lever yieldingly movable in response to resistance of the last to the movement of the band lengthwise thereof and arranged to act in such yielding movement on said band-applying levers to swing them widthwise of the last and thereby cause the band to clamp the upper against the side faces of the last.

25. In a machine for operating on shoes, the combination with a band for embracing and clamping an upper about an end of a last, of band-applying levers arranged to extend heightwise of the last and connected to the ends of said band, an operating lever movable to swing said band-applying levers lengthwise of the last to cause the band to clamp the upper against the end face of the last, and a toggle providing a fulcrum for said operating lever and yieldingly movable in a direction to straighten it in response to resistance of the last to the movement of the band lengthwise thereof, said toggle being arranged to act in its yielding movement on said band-applying levers to swing them widthwise of the last and thereby cause the band to clamp the upper against the side faces of the last.

JOHN WILLIAM PRATT.

WILLIAM ARTHUR BARKER.
